SHOE TREE

Filed July 29, 1946

UNITED STATES PATENT OFFICE

2,459,592

SHOE TREE

Robert H. Slavin, Dayton, Ohio

Application July 29, 1946, Serial No. 686,994

4 Claims. (Cl. 12—128.6)

1
This invention relates to shoe trees.

An object of this invention is to provide a shoe tree having an adjustable heel and toe support engaging member and a handle for the shoe tree for attaching the shoe tree to a wall bracket.

Another object of this invention is to provide a shoe tree having an adjustable and pivoted center section with a toe section pivotally connected thereto, a handle on the center section, with a hook member on the rear of the handle for attaching the shoe tree to a wall and a pivoted locking member on the handle for locking the shoe tree rigid on the handle.

Still another object of this invention is to provide a shoe tree of the kind to be hereinafter described, for supporting a shoe for the conventional purpose of shoe trees and a handle and lock for rigidly supporting the shoe from a wall bracket for polishing the shoes.

With the above and other objects in view, my invention consists in the arrangement, combination and details of construction disclosed in the drawings and specification, and then more particularly pointed out in the appended claims.

In the drawings,

Figure 1 is a side elevation, partly in section and partly cut away, of a shoe tree constructed according to an embodiment of my invention.

Figure 2 is a top plan view.

Figure 3 is a section taken on the line 3—3 of Figure 1.

Figure 4 is a section taken on the line 4—4 of Figure 1.

Figure 5 is a front elevation of a wall bracket, and

Figure 6 is a top plan view thereof.

Referring to the drawings, the numeral 10 designates generally a shoe tree constructed according to an embodiment of this invention. The shoe tree 10 comprises a forward hollow shell shaped or forwardly tapered arcuate toe engaging section 11 having perforations 12 therethrough for permitting the circulation of air in the shoe whereby the inside of the toe section of the shoe may be exposed to circulating air. Near the rear or wider end of the toe section 11, a pair of oppositely disposed downwardly extending apertured lugs or ears 14 are struck therefrom on opposite sides of the longitudinal median of the toe section 11.

A rearwardly extending inverted U-shaped channel or toe member supporting bar 15 is pivotally connected to the member 11. The bar 15 is formed of an elongated U-shaped bar or member having the arms tapered toward the bight at the

2
front end thereof and the bight is extended forwardly and reverted downwardly to form a hinge barrel 16. A hinge or pivot pin or bolt 17 engages through the ears 14 and barrel 16 for pivotally connecting the bar 15 to the toe member 11.

A rear substantially oval vertically disposed shoe heel engaging member 18 is provided and a forward extending inverted U-shaped channel or heel member supporting rod 19 is secured to the heel member 18 by rivets, welding, or other suitable attaching means. The heel supporting member 19 is larger than the member 15 whereby the member 15 may be telescopically adjusted therein. The downwardly extending arms of the member 19 are provided with oppositely disposed aligned openings 20 through which a screw 21 may engage for pivotally connecting the rear end of the toe member supporting bar 15 in selected position.

A substantially L-shaped handle 22 formed of a U-shaped strip of metal is secured to the forward end of the heel member supporting bar 19 and extends upwardly and rearwardly therefrom, the rearwardly extending arm 24 extending well beyond the heel member 18 and having fixed at its rear end a hook member 25. The hook member 25 is formed of an inwardly extending center section 26 having oppositely extending arms 27 on each side thereof for engaging in a wall bracket.

On the forward side of the vertical arm 28 of the handle 22 there is provided a hook member 29 which is rockably secured thereon by a pivot pin 30. The member 29 is formed at its upper end with a rearwardly extending U-shaped finger engaging section 31, and at its lower end with an inwardly opening hook 32 which is adapted to engage under the lower edge of the downwardly extending arms of the supporting bars 15 and 19 for holding these supporting members against pivoting movement relative to each other.

In the use of this shoe tree 10, when the bars 15 and 19 are adjusted for the proper desired length by engaging the screw 21 in the selected openings 20, the toe member 11 is pressed into the shoe and the heel member 18 pressed into place. The bars 15 and 19 are aligned by pressing the pivot 21 downwardly and the hook 32 is rocked transversely of the members 15 and 19, for locking them in aligned position. The hook member 25 is then engaged in a suitable wall bracket 34 to support the shoe tree 10 and shoe from the wall in a rigid position where it may readily be polished.

A typical wall bracket is shown in Figures 5 and 6 wherein the bracket 34 comprises a flat

piece of metal which is adapted to be secured flat on a wall by bolts through the openings 35. The rear side of the bracket 34 adjacent the wall or support is formed with a wide vertical slot 36 in which the arms 27 are adapted to slidably engage from the top of the bracket and a narrow slot 37 in the front of the bracket 34 communicates with the slot 36. The slot 37 extends only part way down the height of the bracket 34 and the center section 26 of the hook 25 is adapted to engage therein for supporting the shoe tree 10 on the bracket 34.

Without attaching the shoe tree to a wall bracket, the handle 22 provides a handle for handling the shoes and locking the shoe tree in aligned shoe supporting position.

I do not mean to confine myself to the exact details of construction herein disclosed, but claim all variations falling within the purview of the appended claims.

What I claim is:

1. A shoe tree of the kind described, comprising a toe member, a heel member, a rearwardly extending U-shaped toe member supporting bar pivotally connected to said toe member, a forwardly extending U-shaped heel member supporting bar fixed to said heel member, said toe member supporting bar telescopingly engaging said heel member supporting bar, means pivotally connecting said bars together at selected positions along the length thereof, an L-shaped handle fixed to the forward end of said heel supporting member extending upwardly and rearwardly therefrom, a transversely rockable bar locking member rockably carried by said handle for locking said bars against pivoting movement in aligned position and means fixed to the rear end of said handle for attaching said shoe tree to a wall bracket.

2. A shoe tree of the kind described, comprising a toe member, a heel member, a toe member supporting bar pivotally connected to said toe member, a heel member supporting bar fixed to said heel member, means connecting said toe member supporting bar on said heel member supporting bar for pivoted movement at selected positions along the length thereof, a handle on the forward end of said heel supporting member, a locking

member engageable with said toe supporting bar, and means pivotally mounting said locking member on said handle for swinging transversely of the axes of said bars whereby to lock said bars in aligned position.

3. A shoe tree of the kind described comprising a toe member, a heel member, a toe member supporting bar pivotally connected to said toe member, a heel member supporting bar, means pivotally connecting said supporting bars together, a locking member on one of said supporting bars, means pivotally mounting said locking member on said one bar for swinging transversely of the longitudinal axes of said bars and into engagement with the other bar for locking said bars in aligned position.

4. A shoe tree of the kind described comprising a toe member, a heel member, a toe member supporting bar, a heel member supporting bar, means pivotally connecting said supporting bars together, a locking member on one of said supporting bars, means pivotally mounting said locking member on said one bar for swinging transversely of the longitudinal axes of said bars and into engagement with the other bar for locking said bars in aligned position.

ROBERT H. SLAVIN.
